PIN SPOT MARKER FOR BOWLING ALLEYS

William White, Newark, N. J.

Application February 3, 1948, Serial No. 5,916

5 Claims. (Cl. 273—52)

1

This invention relates to bowling alleys, and the invention has reference, more particularly, to improvements in spot markers for bowling alleys.

The invention has for an object to provide a novel and simple construction of pin spot device or marker which is adapted to indicate the proper position of a given pin in its relation to the conventional symmetrical group of tenpins as stood upon an alley floor ready to be bowled against; the novel pin spot device or marker being relatively highly resistant to wear as compared with the wood surface of the alley; and the novel pin spot device or marker being so constructed as to be self-binding against displacement from its operative relation to the alley floor, when countersunk and imbedded in the latter, and yet being adapted to be not only easily and quickly mounted in the alley floor, but as easily and quickly released therefrom for adjustment, or removal and replacement.

The invention has for another object to provide a novel and simple pin spot device or marker consisting of but two cooperative parts comprising a radially expandible socket element and a central tapered expander element or core; said parts having cooperative screw-threaded means for coupling the same in operative assembled relation.

The invention has for a further object to provide a pin spot device or marker, of the character referred to, which is provided with an axial opening or passage through which a retractible pin positioning guide element may be projected.

Other objects of this invention, not at this time more particularly enumerated, will be understood from the following detailed description of the same.

An illustrative embodiment of this invention is shown in the accompanying drawings, in which:

Fig. 1 is a plan view of the novel pin spot device or marker as operatively imbedded in the floor of a bowling alley; Fig. 2 is a transverse, vertical section, taken on line 2—2 in Fig. 1, but showing the pin spot device or marker in elevation; Fig. 3 is a view similar to that of Fig. 2, but showing the pin spot device or marker in transverse vertical section; and Fig. 4 is a vertical sectional view, taken on line 4—4 in Fig. 1.

Fig. 5 is a view similar to that shown in Fig. 3, but with the central tapered expander element or core of the pin spot device or marker removed from the expandible socket element thereof; and Fig. 6 is a plan view, viewed downwardly from line 6—6 in Fig. 5.

2

Similar characters of reference are employed in the above described views, to indicate corresponding parts.

Referring to the drawings, the pin spot device or marker of this invention comprises a simple two-part structure provided by a radially expandible socket element and a cooperative expander element or core. The socket element is formed by a body portion 10 which is of cylindrical external shape, and which is closed at its lower end by a bottom wall 11. Said body 10 is preferably, but not necessarily, provided at its upper end with an external, diametrically enlarged, annular head flange 12. The body 10 is internally shaped to provide an upwardly open, downwardly and inwardly tapered, axial socket 13, which terminates at the bottom wall 11. The side walls of the body 10, contiguous to the socket 13, are provided with a plurality of circumferentially spaced radial slits 14, thus dividing said side walls into a plurality of outwardly yieldable wall sections 15 which are adapted, under applied internal pressure or thrust, to be projected radially, whereby to expand the socket element for purposes hereinafter explained. The bottom wall 11 of the body 10 is provided with an axially aligned, internally screw-threaded opening 16.

The expander element or core comprises an inverted conical member or core 17, which is adapted to be entered into the socket 13 of the socket element body 10. Said conical member or core 17 is of somewhat less axial length than the axial depth of the socket 13 of said socket element body 10. Extending from the bottom end of the conical member or core 17 is an axially aligned, externally screw-threaded hub 18, which is adapted to screw into the screw-threaded opening 16 with which the bottom wall 11 of the socket element body 10 is provided. The upper end portion 30 of the conical member or core 17 is provided with a pair of laterally spaced, outwardly open wrench sockets 19, so that a suitable spanner wrench (not shown) can be entered therein, and thus operatively applied to the conical member or core 17 40 for turning the same.

The bowling alley, which is to be equipped with the novel pin spot device or marker of this invention, is bored to provide an upwardly open chamber 20 of a diameter to permit insertion therein 50 of the socket element body 10 of said pin spot device or marker. If the socket element body is provided with the annular head flange 12, the upper end of said chamber 20 is counterbored to provide an enlarged annular mouth portion 21 55 for the reception of said head flange 12.

To assemble the pin spot device or marker in affixed operative relation to the bowling alley, the socket element body 10 is entered within the chamber 20 and so disposed therein that its upper end will lie flush with the bowling alley surface. If said body 10 is possessed of the head flange 12, the latter will be received in the mouth portion 21 which, in such case, will be provided in connection with chamber 20; said mouth portion 21 being of a depth equivalent to the height of said head flange, so that, when the latter is seated in said mouth portion, the upper end of the socket element body will be disposed flush with the bowling alley surface. After the socket element body 10 is thus assembled with the bowling alley, the conical member or core 17 is entered in the socket 13 of said body 10, and the screw-threaded hub 18 of the former is opposed to the screw-threaded opening 16 of the bottom wall 11 of said body, ready to be turned down therethrough.

The conical member or core 17 having been thus initially assembled with the socket element body, a spanner wrench is applied thereto to turn the same down into the socket 13 of the latter, as downdrawn by the descent of the screw-threaded hub 18 in the screw-threaded opening 16 of the bottom 11 of said socket element body 10. As the conical member or core 17 moves downwardly through the socket 13, with its tapered external surface in engagement with the internal tapered surface of the latter, said conical member or core will exert a wedging outward thrust against the yieldable wall sections 15 of the body 10, whereby to urge the latter radially outward against the walls of the alley chamber 20. The conical member or core is thus turned down until its upper end becomes aligned in plane or flush with the upper end surface of the body 10. When thus positioned, the conical member or core 17 exerts a maximum thrust upon said side wall sections of the socket element body 10, whereby to set up an exceedingly strong frictional engagement thereof with the walls of the alley chamber 20, and so as to strongly bind the pin spot device or marker to the alley against loosening or displacement. Notwithstanding such strongly bound relation of the pin spot device or marker to the alley, the former may, nevertheless, be quickly and easily released for removal and replacement or for adjustment, merely by withdrawing the conical member or core 17, and thereby relaxing the wall sections 15 so that the body 10 may be easily removed from the alley chamber 20. This possibility is of great advantage, especially when it is desired to dress or re-plane the alley surface.

In many bowling alley installations, provision is made for use of retractable pin positioning guide elements which are normally withdrawn below the surface of the alley, but which can be projected above said surface so as to serve as guides in aid of accurately registering pins with the spots or markers during the operations of manually setting up said pins. The pin spot device or marker of the instant invention may be readily accommodated to admit of the use of such pin positioning guide element. To this end, the conical member or core 17 is provided with an axial passage 22 through which a pin positioning guide element 23 (shown by broken lines in certain of the figures of the accompanying drawings) may be projected and retracted. Preferably such passage 22 terminates at its lower end in a flared mouth portion 24, whereby to assure entrance of such pin positioning guide element 23

upwardly through the pin spot device or marker in properly aligned axial relation thereto.

From the above, it will be obvious that the instant invention provides a very simple and easily mounted and dismounted pin spot device or marker for bowling alleys. It will also be understood that various changes could be made in the detail construction of the above described illustrative embodiment of the invention without departing from the scope of the here-following claims.

Having now described my invention, I claim:

1. A pin spot device for bowling alleys comprising a socket element having an upwardly open, downwardly and inwardly tapered socket bounded by radially split side walls, and an inverted conical core within said socket having a screw-threaded connection with the bottom of the socket element, whereby rotation of the core in down moving direction relative to the socket element expands the split side walls of the latter into frictionally bound anchoring engagement with the walls of an opening in an alley provided for the reception of said socket element.

2. A pin spot device for bowling alleys comprising a body adapted to be countersunk in an opening in the alley level with the surface of the latter, said body having an upwardly open, axially disposed and downwardly and inwardly tapered socket, said body having a bottom wall and radially split side walls bounding said socket, the bottom wall having an internally screw-threaded opening axially aligned with said socket, and an inverted conical core having a screw-threaded hub at its lower end to screw into said screw-threaded opening so as to draw said core into said socket, and thereby expand the split side walls of said body into frictionally bound anchoring engagement with the walls of said alley opening.

3. A pin spot device for bowling alleys comprising a body adapted to be countersunk in an opening in the alley level with the surface of the latter, said body having an upwardly open, axially disposed and downwardly and inwardly tapered socket, said body having a bottom wall and radially split side walls bounding said socket, the bottom wall having an internally screw-threaded opening axially aligned with said socket, an inverted conical core having a screw-threaded hub at its lower end to screw into said screw-threaded opening so as to draw said core into said socket, and thereby expand the split side walls of said body into frictionally bound anchoring engagement with the walls of said alley opening, and said core having a passage extending axially therethrough to accommodate a movable pin positioning guide element.

4. A pin spot device for bowling alleys comprising an externally cylindrical body having an external annular head flange at its upper end, said body being adapted to be disposed in an opening in an alley with its head flange countersunk in a counterbored portion of said alley opening flush with the alley surface, said body having an upwardly open, axially disposed and downwardly and inwardly tapered socket, said body having a bottom wall and radially split side walls bounding said socket, the bottom wall having an internally screw-threaded opening axially aligned with said socket, and an inverted conical core having a screw-threaded hub at its lower end to screw into said screw-threaded opening so as to draw said core into said socket, and thereby expand the split side walls of said body into fric-

tionally bound anchoring engagement with the walls of said alley opening.

5. A pin spot device for bowling alleys comprising an externally cylindrical body having an external annular head flange at its upper end, said body being adapted to be disposed in an opening in an alley with its head flange countersunk in a counterbored portion of said alley opening flush with the alley surface, said body having an upwardly open, axially disposed and downwardly and inwardly tapered socket, said body having a bottom wall and radially split side walls bounding said socket, the bottom wall having an internally screw-threaded opening axially

aligned with said socket, an inverted conical core having a screw-threaded hub at its lower end to screw into said screw-threaded opening so as to draw said core into said socket, and thereby expand the split side walls of said body into frictionally bound anchoring engagement with the walls of said alley opening, and said core having a passage extending axially therethrough to accommodate a movable pin positioning guide ele-

10 ment.
